UNITED STATES PATENT OFFICE.

FRIDRICH W. G. BOETTCHER, OF DETROIT, MICHIGAN.

COMBINED SKATE AND KNIFE SHARPENER.

SPECIFICATION forming part of Letters Patent No. 594,723, dated November 30, 1897.

Application filed October 16, 1897. Serial No. 655,415. (No model.)

To all whom it may concern:

Be it known that I, FRIDRICH W. G. BOETTCHER, a citizen of the United States, residing at Detroit, in the county of Wayne and State 5 of Michigan, have invented certain new and useful Improvements in a Combined Skate and Knife Sharpener; and I do hereby declare the following to be a full, clear, and exact description of the invention, such as will enable 10 others skilled in the art to which it appertains to make and use the same.

My invention relates to a combined skate and knife sharpener; and it consists of certain novel constructions, combinations, and arrangements of parts, as will be hereinafter described and specifically claimed.

In the accompanying drawings, Figure 1 is an end view of my improved sharpener. Fig. 2 is a side view of the same, and Fig. 3 is a 20 perspective view of the sharpener arranged within a suitable base or support.

A in the drawings represents my improved sharpener, which consists, preferably, of a metallic frame composed of a longitudinally-extending U-shaped piece *a*, having side extensions *a'* *a'*, forming strengthening-ribs. A round, elliptical, or other suitably-shaped file *B* is journaled or otherwise suitably secured, preferably so as to rotate, between the downwardly-projecting end extensions *a*² of the frame. The file, which is preferably made cylindrical in cross-section, is formed on its ends concentrically of the same with slight depressions *b*, into which the ends of screws 35 *C* rest, which screws when tightened up prevent the file from revolving, but which when unloosened permit the file to be revolved to present a new sharpening-surface.

To the frame *A* at both ends are secured 40 guides *D*, which extend the entire length of the machine and upwardly alongside the roller on both sides to form knife-guides, as shown at *d*, and downwardly to form a skate-guide, as at *d'*, below the file-roller. It will be 45 seen from an inspection of Fig. 1 that a V-guide for a knife is formed on opposite sides of the file-roller and that to sharpen the knife it is simply necessary to pass the knife several times through the right-hand guide and then 50 pass it through several times the left-hand guide, when the knife will be found to be perfectly sharpened. It will also be seen that

a perfect skate-guide is formed below the file-roller, and by passing the runner of a skate through the same, as shown in Fig. 1, the skate 55 will be readily sharpened.

The forming of a combined knife and skate guide in one structure I regard as an important feature of my invention. The guides can be drawn toward each other or separated 60 more or less by means of a screw *F*, as shown in Fig. 1.

In Fig. 3 I have shown the sharpener supported in a base *G*. This base will be found convenient for holding the machine when a 65 knife is being sharpened. The base is provided with a longitudinal slot *g*, into which the lower or skate-guide portion is inserted, which will steadily hold the sharpener in an upright position and permit a knife to be 70 drawn back and forth through the same. The top surface of the base on one side of the slot is covered with a fine emery surface *g'* and on the other side of the slot is covered with a rough emery surface *g*². These emery surfaces will be found very convenient for putting a fine edge on a knife after it has been brought to a proper edge on the file-roller. 75

The sharpener will be found very convenient for household purposes, being very simple in construction and can be manufactured at a slight cost.

Having now described my invention, what I claim as new, and desire to secure by Letters Patent, is—

85

1. A combined skate and knife sharpener comprising in its construction a suitable frame, a file-roller secured in the same, and a combined knife and skate guide secured to said frame adjacent to the file-roller so that 90 one portion of the guide will serve to direct the movement of a knife along the file-roller and another portion of said guide will serve to direct the movement of a skate over said roller while said knife and skate are being 95 sharpened, substantially as described.

2. A combined skate and knife sharpener comprising in its construction a suitable frame, a file-roller journaled in the same and capable of rotation, and a combined knife 100 and skate guide secured to said frame adjacent to the file-roller so that one portion of the guide will serve to direct the movement of a knife along the file-roller and another por-

tion of said guide will serve to direct the movement of a skate over said roller while said knife and skate are being sharpened, substantially as described.

5 3. A combined skate and knife sharpener comprising in its construction a suitable frame, a file-roller secured in the same, and a combined knife and skate guide secured to said frame adjacent to the file-roller and capable of lateral adjustment so that one portion of the guide will serve to direct the movement of a knife along the file-roller and another portion of said guide will serve to direct the movement of a skate over said roller while said knife and skate are being sharpened, substantially as described.

10 4. A combined skate and knife sharpener comprising in its construction a suitable frame, a file-roller journaled in the same and capable of rotation, and a combined knife and skate guide secured to said frame adjacent to the file-roller and capable of lateral adjustment so that one portion of the guide will serve to direct the movement of a knife along the file-roller and another portion of said guide will serve to direct the movement of a skate over said roller while said knife and skate are being sharpened, substantially as described.

15 5. A combined skate and knife sharpener comprising in its construction a suitable frame, a file-roller secured in the same, a combined knife and skate guide secured to

said frame adjacent to the file-roller so that one portion of the guide will serve to direct 35 the movement of a knife along the file-roller and another portion of said guide will serve to direct the movement of a skate over said roller while said knife and skate are being sharpened, a base provided with a longitudinal slot for engaging the skate-guides and thereby holding the knife-sharpener in an upright position, and sharpening-surfaces on said base, substantially as described.

10 6. A combined skate and knife sharpener 40 comprising in its construction a frame, comprising a longitudinally-arranged U-shaped portion, a file-roller journaled in the same and capable of rotation, means for securing the file-roller against rotation, and a combined knife and skate guide secured to said frame adjacent to the file-roller and capable of lateral adjustment so that one portion of the guide will serve to direct the movement of a knife along the file-roller and another 45 portion of said guide will serve to direct the movement of a skate over said roller while said knife and skate are being sharpened, substantially as described.

15 In testimony whereof I hereunto affix my 50 signature in presence of two witnesses.

FRIDRICH W. G. BOETTCHER.
